UNITED STATES PATENT OFFICE.

FRANZ BURGER AND HENRY M. WILLIAMS, OF FORT WAYNE, INDIANA; SAID BURGER ASSIGNOR OF ONE-HALF OF HIS RIGHT TO SAID WILLIAMS.

SOUND-FINDER.

SPECIFICATION forming part of Letters Patent No. 645,067, dated March 13, 1900.

Application filed December 6, 1898. Renewed July 31, 1899. Serial No. 725,691. (No model.)

To all whom it may concern:

Be it known that we, FRANZ BURGER and HENRY M. WILLIAMS, citizens of the United States, residing at Fort Wayne, in the county 5 of Allen and State of Indiana, have invented certain new and useful Improvements in Sound-Finders, of which the following is a specification.

Our invention relates to devices for ascertaining the source of sound; and it consists of a sound-receiver having a transverse tube open at the outer end and closed at the center, with earpieces and tubular connections between the ends of the said divided tube, as 10 fully set forth hereinafter and as illustrated in the accompanying drawings, in which—

Figure 1 is a view in part section, illustrating our improved sound-finder in one construction. Fig. 2 is a sectional view showing 15 the improved sound-finder as differently constructed to serve also as a receptacle for liquids.

In the construction shown in Fig. 1, A is a plate or disk, which may be solid or hollow, 20 low and through which extends an opening or tube a, divided in the center by a diaphragm or partition b, so that the said tube is open at each outer end toward one side of the said plate or disk. This plate or disk we 25 denominate a "receiver," inasmuch as it supports the receiving-tube a and as it may be either a solid block or plate or may be hollow, constituting a receptacle for liquid, as set forth hereinafter. With each section of the 30 tube a, on opposite sides of the partition b, communicates a tube c, and from the outer end of each tube a flexible tube E extends and is provided at its outer end with a suitable earpiece F. When these earpieces are 35 applied to the ears and the receiver A is held in the hand and pointed in the direction from which a sound proceeds, the fact that the instrument is so pointed will be evidenced by equal impressions produced upon the two ears. 40 If, however, the receiver is turned to one side or the other, so that one end or the other of the tube a is pointed more or less accurately

toward the source of the sound, then in that case the sound will appear louder or be more perceptible to the ear in communication with 50 the end of the tube a which is pointed toward the source of sound, and the direction from which the sound emanates may thus be ascertained in a fog or when for any reason this direction could not otherwise be approximately or accurately determined. 55

In case the device is intended for army use it will be very effective in connection with the use of smokeless powder in determining the source from which the firing proceeds. For 60 such purpose instead of using a separate device we may make use of the ordinary canteen, which constitutes the receiver A, as shown in Fig. 2, the tube a extending through the center of the canteen and the tubes c c branching from the tube a and extending through the casing of the canteen, as shown. In such case the neck e of the canteen (provided with the stopper H) may be situated between the 65 ends of the tubes c c, so as to serve as a convenient handle. In this case the sides of the receptacle may be sunken in, so as to constitute flaring mouths for the ends of the tube a to better collect the sound, as shown in Fig. 2. 70

Without limiting ourselves to the precise construction and arrangement of parts shown, we claim—

1. The within-described sound-finder consisting of a receiver A provided with a transverse tube a, having a central partition, earpieces F, F, and tubular connections between the earpieces and the separate ends of the tube a, substantially as described. 80

2. The combination of the receptacle A, 85 transverse tube a, open at the opposite ends and closed in the center, tubes c c communicating with the different sections of the tube a, and flexible tubes communicating with the tubes c and provided with earpieces, substantially as set forth. 90

3. The combination of the hollow receptacle provided with a neck and stopper, the tubes a extending through the receptacle and

closed at the center, and earpieces, and tubular connections between the latter and the ends of the tube α , substantially as set forth.

4. The combination of the receptacle A, tube α having a central partition and flaring outward at the opposite ends, and earpieces communicating with the different sections of the tube α , substantially as and for the purpose described.

In testimony whereof we have signed our names to this specification in the presence of two subscribing witnesses.

FRANZ BURGER.
HENRY M. WILLIAMS.
